DANIEL SHERWOOD, OF LOWELL, MASSACHUSETTS, ASSIGNOR TO
WOODS, SHERWOOD, AND COMPANY.

Letters Patent No. 92,663, dated July 13, 1869.

IMPROVEMENT IN TOAST-RACK

The Schedule referred to in these Letters Patent and making part of the same.

To all whom it may concern:

Be it known that I, DANIEL SHERWOOD, of Lowell, in the county of Middlesex, and State of Massachusetts, have invented a new and improved Toast-Rack; and I do hereby declare the following to be a full, clear, and exact description thereof, reference being had to the accompanying drawings, figures, and letters of reference thereon, making part of this specification.

Of the said drawings—

Figure 1 is a side elevation of my improved toast-rack.

Figure 2 is an end view of the same.

Similar letters of reference indicate like parts in the drawings.

To enable others skilled in the art to make and use my invention, I will describe the construction thereof.

I first take of twisted wire a proper quantity for the desired size of rack, and form the lower bridge and legs, A C, of a single piece.

I then form the bridge B, the sides and ends, of a single piece of wire.

The rack D is formed of twisted wire, wound upon a cylinder; and a handle, E, is formed, as shown, by twisting the wire together.

The parts are then firmly united by sewing the same together with fine wire, or by soldering, as desired.

The article may be ornamented with the rosettes *a*, or ornaments of any other form, as desired, and the whole is dipped in molten metal and tinned or plated, and the article is light, beautiful, and a strong and durable article of furniture for the table.

I claim, as a new and improved article of manufacture, a toast-rack, constructed of twisted wire, substantially in the manner described and specified.

DANIEL SHERWOOD.
